FREEZING MOLD

Harry H. Moll, Denver, Colo.

Application October 24, 1935, Serial No. 46,501

8 Claims. (Cl. 62—108.5)

This invention relates to improvements in ice molds of the type employed in connection with mechanical refrigerators.

The use of mechanical refrigerators in ordinary dwellings and apartments has already displaced the ordinary ice boxes to a very great extent. Mechanical refrigerators lend themselves very readily to the artificial production of ice, and molds of different kinds are usually provided for freezing small "cubes" of ice for use in preparing cold drinks. It has been found by experience, that although the freezing of water so as to form ice "cubes" of the desired shape and size is an easy matter, it is very difficult to remove such ice cubes from the molds in which they are frozen, particularly when constructed of metal, because the ice will adhere very strongly to the metallic surfaces and make it quite difficult to remove the ice from the mold. To overcome this difficulty, many different kinds of trays have been invented.

It is the object of this invention to produce a mold for use with mechanical refrigerators, of the ordinary household type, and from which the ice can readily be removed.

A further object is the provision of a mold effective for freezing liquid into bodies of spherical shape.

Another object is to provide a mold, for the purpose pointed out, which shall be made in two parts that can be readily brought into operative position, and which can also be readily separated so as to remove the ice therefrom.

The above and any other objects that may become apparent as the description proceeds are attained by means of a construction and an arrangement of parts that will now be described in detail, and for this purpose reference will be had to the accompanying drawing, in which the invention has been illustrated in several specifically different forms, and in which

Figure 1 is a top plan view of a portion of a mold which is constructed in accordance with this invention;

Figure 2 is a longitudinal section, taken on line 2—2, Figure 1;

Figure 3 is a top plan view of another embodiment of the invention;

Figure 4 is a transverse section taken on line 4—4, Figure 3, and shows the mold in closed position;

Figure 5 is a transverse section, similar to that shown in Figure 4, but shows the mold in open position;

Figure 6 is a longitudinal section similar to that shown in Figure 2, but showing a slightly different form of the invention; and

Figure 7 is a fragmentary sectional view illustrating how the mold can be bent for the purpose of removing the ice.

In the drawing, numeral 8 represents the bottom of a metal tray or of an open supporting frame whose ends have been designated by numerals 9. The upper edges of the tray shown in Figure 2 is provided with an outwardly extending flange 10. Located in and supported by the frame or tray, that has just been described, is a mold comprising a single rubber member having inclined end and side walls that engage the corresponding inside walls of the tray or frame. 5

The mold is also provided with outwardly extending flanges 12 that project over and are supported from the flange 10 of the support. The mold is formed with several parallel rows of spherical openings or mold cavities 13 whose walls 15 are provided with circular openings 14 through which the water may enter the molds, and through which the ice spheres must be removed therefrom.

The walls may be provided with one or more cuts 15 that will permit the neck of the mold to spread, in the manner shown in Figure 7, so as to facilitate the removal of the ice spheres therefrom, but where the material of the mold is sufficiently elastic, this is not necessary. 20

When the support for the mold is a watertight tray, the spaces between the individual molds, which have been designated by numeral 16, are closed by the material of the mold, so as to preclude the entry of water into the trays 30 when the molds are filled with water, but when the support is merely an open frame, the spaces 16 may be open.

When a tray like that illustrated in Figures 1, 2 and 7 and which has just been described is 35 used, the mold cavities are filled by pouring water over the upper surface of the mold until the cavities are filled.

After the water has been frozen, the rubber mould is removed from the support, or frame, and flexed, as shown in Figure 7, whereupon the ice spheres will loosen from the sides of the mold, and can be forced out thru the openings 14. 40

In Figures 3, 4 and 5 a two part mold has been illustrated that can be made entirely of metal or 45 of rubber, either flexible or hard; of bakelite or of any other suitable material, but which has been primarily designed to be made from metal, such as aluminum.

This mold is made in two parts, a bottom part 50 A and a cover part B. The part A has a thick bottom 17 surrounded on its four sides by upwardly extending walls 18. The upper surface of the bottom has a plurality of parallel rows of semi-spherical depressions 19. The cover B is 55 substantially of the same thickness as the bottom 17, and fits inside of the walls 18 in the manner shown in Figure 4.

The cover has an outwardly extending flange 60 20 that projects over and beyond the walls 18 in

the manner shown in Figure 4. The cover is connected to one wall of the bottom part A by hinges 21 so that it may occupy either of the positions illustrated in Figures 4 or 5. The under surface 5 of the cover has semi-spherical depressions 19a that correspond in number, and position to the corresponding recesses 19 in the bottom, so that when the cover occupies the position shown in Figure 4, spherical cavities will be formed.

10 The cover has a vent opening 22 in communication with each recess. When the mold illustrated in Figures 3, 4 and 5 is to be prepared for use, water is poured into the space above the bottom, while the top is in the position shown in Figure 5, 15 after which the cover is moved slowly to the position shown in Figure 4. The presence of the vents 22 permits the water to fill the spherical recesses that result from the closure of the cover.

After the water has been frozen, the mold can 20 be opened by the application of a spreading force. If necessary, the mold can be slightly warmed by contact with water, as even hot water applied thereto will not produce any appreciable waste, as the ice is completely enclosed by the mold.

25 In Figure 6 a still further modification has been shown, in which the mold is made of metal or other suitable material, and instead of being made in a single piece, like that shown in Figures 1, 2 and 7, is made in two parts. The lower part 30 has been designated as an entirety by reference character Aa, and the top or cover part by reference character Ba. The bottom part has upwardly extending side and end walls 18a that terminate in outwardly extending flanges 10a that project beyond the walls 9.

The cover Ba is not hinged to the bottom in this construction, but rests upon the bottom portion. The two parts have correspondingly positioned semi-spherical recesses 19 and 19a that 40 supplement each other to form spherical mold cavities. The top is provided with vent openings 22a, through which the water may enter, or air leave the mold cavities.

45 It will be apparent from the above description and the drawing that the ice, instead of being formed into "cubes" is molded into substantially spherical form, and this shape has been found to possess several advantages over the usual shapes, as it has no sharp corners or angles. Spherical pieces of ice are also more desirable than other shapes for use with cold drinks, and since a sphere has the minimum surface for a given volume, the melting will take place slower than 50 for any other shape.

55 The mold illustrated in Figure 6, although primarily designed to be made from metal, can also be made from soft or flexible rubber, and when so made, the ice can be very easily removed.

60 Water, as is well known, attains its maximum density at 4° centigrade, and therefore expands when it freezes. Where the molds are made from rubber, this will stretch to take care of any expansion.

65 In the metallic construction shown in Figures 4 and 6, the parts will simply move apart or separate sufficiently to compensate for the expansion, and the expansion that takes place between 4° and zero, centigrade, or while the water is still 70 liquid, will merely raise the water level in the vents.

The depressions 19 and 19a have been shown

and described as semi-spherical, but they may be concave depressions of any shape.

The molds can be used for freezing water or colored liquids, or for freezing fruits, such as cherries, into spherical ice bodies for decorating and cooling drinks or foods. 5

The molds may also be used for freezing or chilling confections or desserts such as ice cream, chocolate, gelatine and the like.

Rounded bodies of ice are also useful in facial 10 massage and ice packs.

Having described the invention, what is claimed as new is:

1. A mold for freezing matter in spherical form, comprising a support having upwardly extending walls, a rubber mold positioned in the support and provided with flanges projecting over the tops of the walls, the mold having a plurality of substantially spherical cavities open at the top for the reception of matter to be frozen, the material being elastic, for permitting the frozen matter to be removed from the cavities. 15

2. A mold for freezing matter in spherical form, comprising a support having upwardly extending walls, a rubber mold positioned in the support and provided with flanges projecting over the tops of the walls, the mold having a plurality of substantially spherical cavities open at the top 20 for the reception of matter to be frozen, the material being elastic and having notches about 30 the opening into the cavities to facilitate the spreading of the material when removing the frozen matter.

3. An elastic one-piece mold for forming substantially spherical pieces of frozen matter, comprising a rubber member provided with substantially spherical cavities, open at the top, the openings being smaller than the diameters of the cavities, and stretchable for the removal of 35 the frozen matter therefrom. 40

4. An elastic one-piece mold for forming substantially spherical pieces of frozen matter, comprising a rubber member provided with substantially spherical cavities, open at the top, the openings being smaller than the diameters of the cavities, the material surrounding the openings being notched to facilitate the removal of 45 the frozen matter therefrom. 50

5. A freezing mold comprising a flexible and stretchable body having an open substantially spherical cavity for the reception of matter to be frozen, the opening being of lesser diameter than the cavity. 55

6. A freezing mold comprising a flexible and stretchable body having an open substantially spherical cavity for the reception of matter to be frozen, the opening being of lesser diameter than the cavity, and a relatively rigid support for the body. 60

7. A freezing mold comprising a flexible and stretchable body having open substantially spherical cavities for the reception of matter to be frozen, the openings being of lesser diameter than the cavities, and a relatively rigid support for the body. 65

8. A freezing mold comprising a flexible and stretchable body having a plurality of substantially spherical cavities open at the top for the reception of matter to be frozen, the openings being of lesser diameter than the cavities. 70
